Primary Examiner — Mary Ann Calabrese(74) *Attorney, Agent, or Firm* — Banner & Witcoff, Ltd.(57) **CLAIM**

The ornamental design for a dispenser, as shown and described.

DESCRIPTION

FIG. 1 is a front, left perspective view of a dispenser showing our new design;

FIG. 2 is a front view thereof;

FIG. 3 is a left side view thereof, wherein the right side is a mirror image of FIG. 3;

FIG. 4 is a rear view thereof; and,

FIG. 5 is a top view thereof.

The broken lines immediately adjacent to the shaded area represent unclaimed boundaries of the design and form no part of the claimed design.

1 Claim, 5 Drawing Sheets(56)
